GRATING FOR RUNNING BOARDS

Alfred Claude Tuttle, Montreal, Quebec, Canada
Application March 26, 1956, Serial No. 574,000

3 Claims. (Cl. 94—30)

This invention relates to improvements in gratings and particularly to gratings used in running boards, catwalks and the like where strength and rigidity are required to withstand heavy loading and rough usage.

The invention consists essentially in the production of an open-work grating from a one-piece sheet of metal by slitting and bending along predetermined lines to give the desired openings and depth of grating to suit particular requirements and having a uniformly level tread surface. The tread surface resulting from the slitted and folded sheet of metal can have either smooth edges or serrated edges depending upon the ultimate use of the grating.

The slit and bent one-piece construction results in the tread surface being formed of a multiplicity of edges of the metal or folded portions producing tread edges thereby giving maximum wearing qualities and friction surface with the result that lightweight metals such as aluminum can be used thereby greatly reducing the total weight of the grating and its cost per lb. of weight.

The object of the invention is therefore to provide a light weight grating of maximum strength from a one-piece sheet metal.

A further object of the invention is to provide a grating which can be formed into any desired shape of edge formed openings of any desired depth.

A further object of the invention is to provide a grating of one-piece construction which requires no fastening by rivets, bolts or welding except securing to an edge binding or such like support structure.

A further object of the invention is to provide a one-piece grating structure whose openings are formed of smooth vertical surfaces to allow unhindered passage downwards for snow, mud and fairly large aggregate of sand, rock or stone and thereby prevent bridging effect of these elements which would tend to close the formed apertures.

These and other objects of the invention will be apparent from the following specification and the drawings forming a part thereof, in which—

Fig. 1 is a partial length of sheet metal showing a method of slitting and bending the sheet to produce a grating in which the tread edges form continuous rigid lines lengthwise and across the grating for maximum strength in all directions.

Fig. 2 is a view of the sheet illustrated in Fig. 1 after it is slit and bent and partly folded in a direction transversely of the lengthwise bends.

Fig. 3 shows the sheet of Figs. 1 and 2 fully bent to form the rigid lengthwise tread edges and showing an intermediate lengthwise tread pulled in the direction of the arrow.

Fig. 4 is a partial detail of a completed grating formed from the sheet shown in Fig. 1.

Referring to the drawings, the sheet 40 can be of any suitable metal but preferably of lightweight metal such as aluminum. The sheet can be of any width or length,

the limit of size being controlled by the size of the equipment necessary to slit, punch and form the sheet.

The sheet 40 is first marked off by either direct marking, but preferably by template.

5 In order to meet certain specifications requiring a grating to have maximum strength lengthwise and transversely across the grating, which specifications can best be met by a grating having tread edges formed of continuous lines lengthwise and transversely across the grating, the
10 method of slitting and bending the sheet is illustrated in Figures 1 and 2 of the drawings. In this method the sheet 40 is slit along the heavy marked lines 41. Each slit formed along the lines 41 comprises two parallel sections 41a and 41b running longitudinally of the sheet and
15 spaced apart from each other and offset longitudinally from each other, the ends of the slit sections 41a and 40b adjacent each other being joined by a transverse slit section 41C. A portion of the slit sections 41a and 41b in each longitudinal row of slits overlap the oppositely disposed section of the next adjacent slit 41 for approximately half the length of the slit sections 41a and 41b as shown in Figure 1. The slits 41 in one longitudinal line are reversed in relation to the slits 41 in the next adjacent longitudinal line so that, referring to the two
25 lines of slits shown in Figure 1, the slit sections 41a in both lines lie parallel with and directly opposite each other while the slit sections 41b are spaced apart from each other and separated by the next intervening slit sections 41a. The sheet 40 is also slit in a longitudinal direction at the ends of the sheet at 42 and 43 to complete the pattern of slitting to the ends of the sheet.

After the sheet has been slit as above described, the sheet is then bent in a lengthwise direction along the lines 44 coincident with the longitudinal lines of the slit sections 41a and 41b and along the lines 45 midway between the lines of bending 44. The bends along the lines 44 and 45 are alternatively made in a reverse direction so that the sheet 40 will take a corrugated form through the stage shown in Figure 2 to the stage shown in
40 Figure 4.

In forming the reverse bends of the sheet 40 reference is made to Figure 1. The sheet is bent downwards along the top line 45 so that the line 45 forms the crest of the corrugations 50 while sheet is bent upwards along the
45 second line 45 so that this second line 45 forms the depth of the corrugation 51 as the sheet is bent into and through the form shown in Figure 2. Each succeeding line 45 of the sheet is bent in a reverse direction from the adjacent line 45.

50 Secondary bends are now formed in the sheet 40. These secondary bends are formed transversely of the bends along the lines 44 and 45 and are along the lines 46 between the lengthwise sections of slits 41a and 41b. Each adjacent pair of bends along the lines 46 are formed in a reverse direction to each other to form the panels 47, 48 and 49 with the panels 48 forming a web member between the adjacent corrugations 50 and 51 of the sheet as shown in Figure 2 when the sheet is partly bent longitudinally and transversely as above described.

60 After the sheet 40 is slit and bent so that the lengthwise corrugations 50 and 51 are completely closed vertically to form the longitudinal tread members as shown in Figure 3, the tread members 50 are of double sheet thickness with the sheet being bent downwardly so that the bend of the sheet is in the top plane of the finished grating and the tread members 51 are of double sheet thickness with the sheet being bent upwardly so that the bend of the sheet is in the bottom plane of the finished grating. The panels 47 and 49 are bent at the same time into a vertical position flat against the adjacent side of the tread members 50 and 51 to which they are at
70

tached with the web members 48 joining the adjacent tread members as shown in Figure 3.

After the sheet 40 has been bent and takes up the form shown in Figure 3 the tread members 51 are pulled lengthwise in the direction of the grating in the direction of the arrow A to bring the web members 48 into a position at right angles to the tread members 50 and 51 as shown in Figure 4.

The open ends of the grating between the tread members 50 and 51 are closed by bending inwards at right angles the end portion 52 of the outer tread 50 and the end portions 53 of the inner treads, 50 and 51 and welding the ends of these end portions 52 and 53 to the outer ends of the adjacent treads 50 and 51. The ends 52 and 53 when anchored to the treads 50 and 51 hold the grating against displacement in its horizontal plane with the web members 48 holding the double sheet sides of the tread members 50 and 51 from gaping open.

Alternate bending lines are provided with a series of apertures 54 which, when the sheet 40 is bent along these alternate lines to form the double sheet thickness tread members 50 and 51 the apertures 54 form serrations on the top of the treads which serrations may be required for many types of grating applications.

Normally the structure as above described requires no further means of holding the various abutting faces of the sheet together as any distortion tending to separate the abutting faces would have to cause distortion of the web members 48. Each web member 48 is joined vertically to the end members 47 and 49 which in turn are joined horizontally to the tread members 50 and 51 along one edge, the latter horizontal joints alternating between the top and the bottom plane of the grating at each of the web members 48. The strength of the web members and the tread members is a function of the sheet thickness and the designed depth of the grating with respect to the load normally expected to be applied to the grating so that no gaping of the abutting faces of the sheet forming the tread members should be expected and therefore no distortion of the web members. However, should additional securing means be required, these can be effected by spot welding the edges of the abutting faces of the sheet forming the tread member at the location of the web members.

Gratings fabricated in the form above described have equivalent strength both laterally and longitudinally and can be made in any depth to carry maximum loading. The vertical openings in the gratings can be made any size to suit working conditions and the clean lines of the openings will prevent bridging by snow or ice particularly under slush conditions and, should bridging occur, this can be quickly cleared as there are no projecting surfaces within the openings to hold the bridging material. The tread surfaces which are the result of folded over metal presenting alternatively rounded surfaces and two separate metal edges brought together, but all being in the same horizontal plane, provide a smooth tread surface for the grating which is not detracted from by the serrations of the tread surface provided for greater footing safety.

What I claim is:

1. In a grating for use on running boards or the like formed from a single sheet of metal slit and bent alternatively upwardly and downwardly relative to the plane of the sheet to form a series of vertically disposed longitudinal tread members, the said longitudinal tread members being formed of double sheet thickness with the bend of the sheet of alternate tread members being disposed on the top horizontal plane of the grating and the bend of the sheet on intervening tread members being disposed on the bottom horizontal plane of the grating, and web members joining said longitudinal tread members at spaced intervals lengthwise of the grating, the said web members having two end portions formed from the sheet extended from the adjacent longitudinal tread mem-

bers and bent into a vertical plane against said longitudinal tread members, one end portion of each web member being offset relative to the other lengthwise of the longitudinal tread members and a joining portion connecting the adjacent vertical edges of the said end portions of the web members, the said joining portions of the web members being disposed at right angles to said longitudinal tread members with the end portions joining alternate longitudinal tread members being bent downwardly relative to the top horizontal plane of the grating while the end portions joining intervening longitudinal tread members being bent upwards relative to the bottom horizontal plane of the grating, the said joining portions of the web members holding the double sheet sides of said longitudinal tread members and the end portions of the web members in close abutment with each other and in spaced parallel relation to adjacent longitudinal tread members, the said longitudinal tread members having their end portions bent at right angles and secured to the ends of adjacent longitudinal tread members to close the ends of the grating and hold said grating in its formed position.

2. In a grating for use on running boards or the like formed from a single sheet of metal slit and bent alternatively upwardly and downwardly relative to the plane of the sheet to form a series of vertically disposed longitudinal tread members, a series of horizontally extending spaced lines of slits, each of the slits in each line including parallel longitudinally extending end portions offset from each other in the longitudinal direction of the grating and an intermediate transversely extending portion extending between and interconnecting adjacent ends of said longitudinally extending end portions of the slits, the parallel end portions of the slits overlapping the end portions of the adjacent slits in the same longitudinal line, the superposed slits in the next adjacent horizontal line of slits being offset in a reverse direction from the superposed slits in adjacent lines, the said longitudinal tread members being formed of double sheet thickness with the bend of the sheet of alternate tread members being disposed on the top horizontal plane of the grating and the bend of the sheet on intervening tread members being disposed on the bottom horizontal plane of the grating, and web members joining said longitudinal tread members at spaced intervals lengthwise of the grating, said web members being formed from that portion of the sheet between the overlapping slits in the same longitudinal line and having two end portions formed from the sheet extended from the adjacent longitudinal tread members and bent into a vertical plane against said longitudinal tread members, one end portion of each web member being offset relative to the other lengthwise of the longitudinal tread members and a joining portion connecting the adjacent vertical edges of the said end portions of the web members, the said joining portions of the web members being disposed at right angles to said longitudinal tread members with the end portions joining alternate longitudinal tread members being bent downwardly relative to the top horizontal plane of the grating while the end portions joining intervening longitudinal tread members being bent upwards relative to the bottom horizontal plane of the grating, the said joining portions of the web members holding the double sheet sides of said longitudinal tread members and the end portions of the web members in close abutment with each other and in spaced parallel relation to adjacent longitudinal tread members, the said longitudinal tread members having their end portions bent at right angles and secured to the ends of adjacent longitudinal members to close the ends of the grating and hold said grating in its formed position.

3. In a grating for use on running boards or the like formed from a single sheet of metal slit and bent alternatively upwardly and downwardly relative to the plane of the sheet to form a series of vertically disposed longi-

tudinal tread members, the said longitudinal tread members being formed of double sheet thickness with the bend of the sheet of alternate tread members being disposed on the top horizontal plane of the grating and the bend of the sheet on intervening tread members being disposed on the bottom horizontal plane of the grating, a series of apertures disposed along the lines forming the top edges of the longitudinal tread members, the said apertures forming a rough serrated tread surface to said tread members, and web members joining said longitudinal tread members at spaced intervals lengthwise of the grating, the said web members having two end portions formed from the sheet extended from the adjacent longitudinal tread members and bent into a vertical plane against said longitudinal tread members, one end portion of each web member being offset relative to the other lengthwise of the longitudinal tread members and a joining portion connecting the adjacent vertical edges of the said end portions of the web members, the said joining portions of the web members being disposed at right angles to said longitudinal tread members with the end portions joining alternate longitudinal tread members being bent downwardly relative to the top horizontal plane of the grating while the end portions joining intervening longitudinal tread members being bent upwards relative

to the bottom horizontal plane of the grating, the said joining portions of the web members holding the double sheet sides of said longitudinal tread members and the end portions of the web members in close abutment with each other and in spaced parallel relation to adjacent longitudinal tread members, the said longitudinal tread members having their end portions bent at right angles and secured to the end of adjacent longitudinal tread members to close the end of the grating and hold said grating in its formed position.
